CLAIM

The ornamental design for a sliding abdominal machine, as shown and described.

DESCRIPTION

FIG. 1 is a front, right perspective view of a sliding abdominal machine showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof; and,

FIG. 7 is a bottom plan view thereof.

(Continued)

The broken lines illustrate portions of the sliding abdominal machine which form no part of the claimed design.

1 Claim, 7 Drawing Sheets
